UNITED STATES PATENT OFFICE.

WORTH H. GURNEY AND JOSEPH P. RUMMEL, OF MANSFIELD, OHIO.

SUSPENDER-BUCKLE.

SPECIFICATION forming part of Letters Patent No. 426,376, dated April 22, 1890.

Application filed January 16, 1890. Serial No. 337,048. (No model.)

To all whom it may concern:

Be it known that we, WORTH H. GURNEY and JOSEPH P. RUMMEL, citizens of the United States of America, residing at Mansfield, in the county of Richland and State of Ohio, have invented certain new and useful Improvements in Suspender-Buckles; and we do hereby declare the following to be a full, clear, and exact description of the invention, such as will enable others skilled in the art to which it appertains to make and use the same, reference being had to the accompanying drawings, and to letters of reference marked thereon, which form a part of this specification.

This invention has reference to suspender-buckles; and it consists in the improvements hereinafter described and set forth, whereby a simple and efficient buckle is provided that will securely clamp the strap and will not be liable to become unfastened or loosened.

In the accompanying drawings, forming part of this specification, Figure 1 is a perspective view of the improved buckle, showing the latch unfastened and the keeper swung open, and Fig. 2 is a front view showing the same clamping a suspender-strap.

The main frame A of the device consists of a single piece of wire bent to form the lower depending hook *a* and upper rectangular portion presenting vertical parallel sides *b*, the top cross-bar *c* being formed by bending in the free ends, which are rigidly connected together by a sleeve *d*, having a front depending lip *e*. The sides *b* are bent inward at about their centers to furnish the bearing for the turned ends of a rigid transverse bar *B*, the upper and lower edges of which are bent horizontally outward to provide two rows of serrations *f*, which said bar carries.

On one of the sides *b*, above and below the connection of the bar *B* therewith, are rigidly secured vertical loops *g*, with which engage the oppositely-turned ends *h* of a swinging keeper *C*, made from a single piece of wire, and the transverse free portion of which is contracted and adapted to be moved parallel with the bar *B*, as shown in Fig. 2. The contracted portion is slightly spread at about its center for the reception of the shank of a projection *i*, formed on the rear side of a latch-lever *D*, the end of the projection being riv-

eted to prevent its withdrawal, but permitting a pivotal movement of said lever upon the keeper. The lever *D* has formed on its long end, by stamping, a lug *j*, which is adapted to engage with a hook *a* when turned parallel with the sides of the buckle, as shown in Fig. 2.

In use, the keeper being in the position represented in Fig. 1, the buckle is adjusted upon the strap. The keeper is then closed upon the strap against the bar *B*. The latch-lever *D* is then turned to a vertical position, so that its upper end is forced beneath and engages the lip *e*, while its lower end is sprung beneath the lower hook *a*, the lug *j* resting in the spread portion of said hook, and thus furnishing additional precaution against accidental detachment.

From the foregoing it will be readily understood that the adjustment can be quickly made, since the latch can be easily detached, the buckle shifted, and the parts again secured. By having the latch-lever operate at right angles to the horizontal keeper a central pivotal connection is secured for said lever, while both ends may be positively engaged and secured.

This invention will be readily distinguished from a prior construction, where the keeper is hung to the top bar and carries a sliding latch to engage the lower hook, for in such prior device the depending keeper has to carry lateral portions to clamp the strap against the rigid horizontal bar. Moreover, the position and engagement of the latch are such that it is liable to be caught by the garments and be detached.

Another advantage in the present construction over the construction previously referred to consists in the fact that the keeper is utilized as a fulcrum, while both ends of the latch-lever are firmly engaged.

We claim—

1. The combination, in a suspender-buckle, of the main frame provided with a hook and catch, a serrated cross-bar secured to said frame, a horizontal keeper secured to one of the vertical side bars of said frame, and a latch pivoted on said keeper and adapted to be swung to engage said hook and catch to lock the keeper in position, substantially as set forth.
2. The combination, in a suspender-buckle,

of the main frame provided with lower depending hook and upper lip, a serrated cross-bar secured to said frame, a horizontal keeper pivotally connected to one of the vertical sides 5 of said frame, and a latch-lever centrally pivoted to the keeper and adapted to be moved to have its ends engage the hook and lip, respectively, substantially as set forth.

3. The combination, in a suspender-buckle, 10 of the main frame formed of a single piece of wire bent to present the lower depending hook, upper rectangular portion having its top bar formed by the inwardly-bent ends of the wire, a loop for clasping said ends and 15 carrying a lip, a serrated cross-bar rigidly secured to the rectangular portion, a keeper pivotally secured to one of the vertical sides thereof, and a latch-lever centrally pivoted to the keeper and adapted to be turned to have

its respective ends engage the loop and hook, 20 respectively, substantially as set forth.

4. The combination, in a suspender-buckle, 25 of a frame having an upper lip and a spread hook, a serrated cross-bar secured to said frame, a horizontal keeper pivotally connected to one of the vertical sides of said frame, a latch-lever centrally pivoted in said keeper and having its lower end provided with a lug to engage the spread portion of the hook when the upper end engages with 30 the lip, substantially as set forth.

In testimony whereof we affix our signatures in presence of two witnesses.

WORTH H. GURNEY.
JOSEPH P. RUMMEL.
